UNITED STATES PATENT OFFICE.

JAMES BARTHOLOMEW SLADE, OF RIVERHEAD, NEW YORK.

VENTILATOR.

SPECIFICATION forming part of Letters Patent No. 597,171, dated January 11, 1898.

Application filed June 11, 1896. Serial No. 595,137. (No model.)

To all whom it may concern:

Be it known that I, JAMES BARTHOLOMEW SLADE, a citizen of the United States, and a resident of Riverhead, in the county of Suffolk and State of New York, have invented certain new and useful Improvements in Ventilators, of which the following is a specification, reference being had to the accompanying drawing, forming a part thereof, in which similar numerals of reference indicate corresponding parts.

This invention relates to ventilators; and the object thereof is to provide an improved device of this class which may be employed for the purpose of ventilating buildings, also for ventilating cars or railway-carriages and for ventilating steamboats and other vessels.

The invention is fully disclosed in the following specification, of which the accompanying drawing forms a part, said drawing being a central vertical section of my improved ventilator and also of the roof or covering of a building, railway-carriage, or other structure.

In the drawing forming part of this specification I have shown at 4 a section of the roof of a building, railway-carriage, steamer or other vessel, and in the practice of my invention I form a circular opening therein, in which is mounted a tubular casing 5, which is provided with a flange 6 at its lower end, whereby it is firmly bolted to the roof 4.

The casing 5 extends a predetermined distance above the roof, as shown at 6, and within said casing and arranged concentrically thereof is a tubular sleeve 7, which is supported therein by cross rods or bars 9, whereby air-passages or an annular chamber 10 is formed between said sleeve and the tubular casing 5, or said sleeve and said tubular casing 5 may be formed integrally, and the air-passages 10 may be bored therethrough or otherwise formed therein.

Mounted in the sleeve 7 and rigidly secured thereto is a tube 11, within which and about the middle thereof is fixed a spider or frame 12, and mounted in the upper end of the tube 11 and revoluble therein is an air-ingress tube 13, which is provided with an outwardly curved bell-shaped end 14, and said tube 13 is also provided about midway of its length

with a spider or frame 15, and connected centrally with the spider or frame 15 is a vertical rod 16, which is pivotally supported centrally of the frame or spider 12 in the tube 11. 55

I also employ a hood 17, which is cylindrical in form and the lower end of which incloses the upper end of the tubular casing 5, and the upper end of said hood is conical in form, and the tube 13 passes therethrough, and connected with one side of the upper conical end of the hood 17 is an air-egress tube 18, which communicates with the interior of said hood and which is curved outwardly in the direction opposite to that of the bell-shaped end 65 of the tube 13, and said tubes 13 and 18 are preferably connected by a cross bar or bars 19, which give stability and strength thereto.

The outer end of the tube 18 is provided with a conical cap or hood 20, the apex of 70 which is directed outwardly, and formed in the tube 18 within said cap or hood and in line with the side walls thereof are ports or openings 21, through which the air passes into said tube and out at the end thereof, and mounted on the end of said tube is a wing or vane 22.

As thus constructed it will be seen that the entire upper portion of the ventilator, including the tubes 13 and 18 and the hood 17, is 80 pivotally supported by the rod 16, and said upper portion is free to revolve on its pivotal support, and, by reason of the hood 20, which is conical in form and the apex of which is directed outwardly, and the wing or vane 22, 85 the bell-shaped end of the tube 13 is always held in the direction from which the wind is blowing. The air thus enters the car, building, steamer, or other structure through the tube 13, and the air within said building, car, vessel, or other structure passes out through the air-passages 10 and through the tube 18, and, by reason of the conical hood 20 and the air ports or openings 21, the outside air is collected by said hood and passes through said 90 ports or openings into said tube and out at the end thereof, as clearly shown by the arrows, thus drawing the air out through the tube 18 and through the hood 17 and the air-passages 10, while at the same time the air passes 100 through the tubes 13 and 11 to fill the vacuum thus formed, and by means of this device the

building, car, or vessel is thoroughly ventilated at all times and provided with a constant supply of fresh air.

My improved ventilator is simple in construction and operation, while being perfectly adapted to accomplish the result for which it is intended; and it is evident that changes in and modifications of the construction herein described may be made without departing 10 from the spirit of my invention or sacrificing its advantages.

Having fully described my invention, I claim as new and desire to secure by Letters Patent—

15 The herein-described ventilator comprising the combination with a roof having a circular opening therein of a tubular casing provided at the lower end with a flange adapted to be bolted to said roof, and internally with a tubular sleeve supported by cross rods or bars thereby forming air-passages between said sleeve and casing, a tube mounted in said sleeve, said tube being provided internally with a spider or frame and at the upper end 20 thereof with a revoluble ingress-tube which is provided with a bell-shaped end, said ingress-tube being provided internally with a 25

spider or frame which is provided centrally with a vertical rod the lower end of which is pivotally supported centrally of the frame or 30 spider 12, said casing being provided with a hood which incloses the upper end thereof, the upper end of said hood being conical in form and having a central opening therein through which said ingress-tube passes, an 35 egress-tube connected with the conical end of said hood, and communicating with the interior thereof, said egress-tube being curved outwardly in a direction opposite to the bell-shaped end of said ingress-tube, and provided 40 at the outer end thereof with means to keep the funnel directed toward the wind, and also provided with means to help draw the air through the said tubes, substantially as herein shown and described.

In testimony that I claim the foregoing as my invention I have signed my name, in presence of the subscribing witnesses, this 30th day of May, 1896.

JAMES BARTHOLOMEW SLADE.
